STRAP FOR LUGGAGE

Anthony N. D'Elia, Riverdale, and Edward M. Stolarz,
Yorktown Heights, N.Y., assignors to Reliable Luggage,
Incorporated

Filed Mar. 1, 1968, Ser. No. 10,796

Term of patent 14 years

Int. Cl. D8—03

U.S. Cl. D8—154

FIG. 1

FIG. 2

FIG. 4

FIG. 3

FIG. 1 is a front elevational view of a strap for luggage embodying our new design, with the strap being in an open position and the bottom portion slightly in perspective;

FIG. 2 is a side elevational view thereof;

FIG. 3 is a front elevational view with the strap being in a closed position with a portion of the strap cut away disclosing the buckle; and,

FIG. 4 is a side elevational thereof on an enlarged scale.

We claim:

The ornamental design for a strap for luggage, as shown.
